RELEASABLE STOP ARRANGEMENT FOR A
MACHINE TOOL

Adolf Spinner, 38 Dachauer Strasse, Munich, Germany

Filed Feb. 13, 1964, Ser. No. 344,608

13 Claims. (Cl. 83—240)

This invention relates to machine tools, and more particularly to a releasable stop arrangement for limiting the travel of a tool slide or the like.

It is known to control the travel of tool slides on cutting machine tools by means of stops which limit the movement of the slides in the several operations of the machine.

The object of the invention is the provision of a releasable stop arrangement which is of simple construction, yet capable of limiting the travel of a tool with great precision.

Another object is a stop arrangement of the type described which is reliable in its operation and has a long useful life without requiring reconditioning.

A further object is the provision of an arrangement including a plurality of individual releasable stops and occupying but a minimum of space in which the several stops operate without interfering with each other.

Yet another object is the provision of a stop arrangement the working elements of which are readily accessible for servicing and maintenance.

With these and other objects in view, the invention, in one of its aspects mainly consists in a stop arrangement including means which define the path of an abutment member mounted on the tool slide to be controlled. Guide rails extend transversely of that path. A blocking member is arranged for movement on the rails, and is urged into engagement therewith by yieldably resilient means while it is being moved toward and away from a path blocking position by suitable actuating means.

Other features and many of the attendant advantages of this invention will be readily appreciated as the same becomes better understood by reference to the following detailed description when considered in connection with the accompanying drawing in which:

FIG. 1 is a sectional plan view of a releasable stop of the invention;

FIG. 2 is an elevational end view of the device of FIG. 1; and

FIG. 3 is a fragmentary, partly sectional plan view of an automatic machine tool equipped with several releasable stops of the type shown in FIGS. 1 and 2.

Referring now to FIGS. 1 and 2 in detail, there is shown a solenoid housing 1 which is a block of hexagonally prismatic shape. The housing 1 carries a similarly shaped coaxial support 2 for the blocking mechanism of the stop. A blind, axially elongated bore 3 in the solenoid housing is aligned with a through bore 4 in the support 2.

A tubular solenoid coil 5 is received in another axially elongated bore of the housing 1 and cooperates with a cylindrical armature rod 6 coaxially received in the coil. The coil 5 and armature 6 are retained in the housing 1 by a plug 7. A threaded spindle 7' extends coaxially from one end of the armature 6 through the plug 7 and may carry a nut, not shown in the drawing, for limiting movement of the spindle 7' inward of the housing 1.

The other end 8 of the armature 6 is of reduced cross section and extends from the housing 1 into an opening of the support 2. The armature end 8 abuts against an arm 9 of a bellcrank lever which is pivoted on the support 2 by a pin 10. The arm 9 is held in engagement with the armature by a torsion spring 17 coiled about the pin 10.

The other arm 11 of the bellcrank lever extends from

the pin 10 beyond the generally hexagonal front face 16 of the support 2. Its free terminal portion 12 is bent so as to be parallel to the pin 10. Respective ends of two flat links 14 are hinged on the lever arm portion 12, and the other ends of the links are pivotally secured to opposite side faces of a cover 13. The cover is pressed against two rails 18 of tungsten carbide by a helical torsion spring 15 mounted on the lever arm portion 12. The rails 18 are set into the front face 16 of the support 2 on opposite sides of the orifice of the bore 4.

When the coil 5 is energized, the armature 6 is attracted inward of the housing 1 against the restraint of the return spring 17. The bellcrank lever 9, 10, 11 is thereby pivoted counterclockwise, as viewed in FIG. 1, and the cover 13 is moved by the links 14 along the rails 18 into a position in which it blocks the orifice of the bore 4.

The cooperation of several stops 20, 21, 22, 23 of the type shown in FIGS. 1 and 2 is illustrated in FIG. 3 which shows as much of an automatic cutting machine tool as is necessary for an understanding of this invention.

A guide rail 26 is a portion of the stationary frame of the machine tool. A tool slide 25 is moved on the guide rail 26 back and forth during normal operation of the machine as indicated by a double arrow. The reciprocating movement of the tool slide 25 is actuated by the drive mechanism of the machine in a manner not in itself relevant to this invention, and not illustrated for this reason. It will be understood that the slide 25 carries a non-illustrated cutting tool.

A carrier 24 is mounted on the slide 25 and supports four abutment pins 20c, 21c, 22c, and 23c which are of different lengths and move longitudinally during the reciprocating movement of the slide 25. The four identical releasable stops 20, 21, 22, 23 are mounted on the machine frame in longitudinal alignment of their respective bores 20a, 21a, 22a, 23a with the abutment pins on the carrier 24. The bore of each stop is constituted by corresponding bores 3 and 4 as shown in FIG. 1.

The cover 20b of the stop 20 blocks the corresponding bore 20a, whereas the covers 21b, 22b, and 23b are in the inoperative position shown in FIGS. 1 and 2. The solenoid of the stop 20 is energized in the illustrated condition of the apparatus.

Operation of the solenoids in the several stops is controlled by a programming unit 27 which is connected to the stops by respective thin-walled steel conduits 20e, 21e, 22e, 23e and by conductors protected by the conduits and not visible in the drawing. The programming unit, the working elements of which are obscured by a cover in FIG. 3, mainly consists of a rotary timing switch connected to a source of electric current and driven by the main drive of the machine tool in a conventional manner selectively to energize the several solenoids in timed sequence in synchronization with the operation of the machine.

The stop arrangement illustrated is capable of arresting movement of the slide 26 in five different positions. Four of these positions are defined by engagement of an abutment pin with a cover which blocks its path, and the fifth by engagement of the longest pin with the end wall of the bore in the associated stop when all covers are in the inoperative position.

While electromagnetic operation of the covers is preferred, it will be appreciated that each solenoid and its armature may be replaced by a piston slidable in a cylinder bore of the housing 1 and having a piston rod extending into the support 2 in the manner of the armature portion 8, and that movement of the pistons may be controlled in a conventional manner by a rotary control valve in the programming unit 27 connected to a source of compressed

air or hydraulic fluid under pressure, and to a vent, as is well known in itself.

The stops of the invention have been found to be capable of reliable operation over extended periods of time without maintenance other than routine lubrication. The narrow guide rails 18 and springs 15 precisely locate the covers 13 in the path of the abutment pins and are not subject to significant wear. There is very little wear on the covers 13 themselves, but the covers are quickly and easily replaced if necessary. The solenoids which are arranged with their axes parallel to the paths of the abutment pins permit the stops to be juxtaposed closely in a minimum of space without mutual interference.

It should be understood, of course, that the foregoing disclosure relates to only a preferred embodiment of the invention, and that it is intended to cover all changes and modifications of the example of the invention herein chosen for the purpose of the disclosure which do not constitute departures from the spirit and scope of the invention set forth in the appended claims.

What I claim is:

1. A releasable stop arrangement for a machine tool and the like comprising, in combination:

- (a) means defining a path of movement for an abutment member;
- (b) two guide rails elongated in a direction transverse of said path and spaced from each other transversely of the direction of elongation thereof;
- (c) a blocking member movable on said guide rails toward and away from a position in which said blocking member blocks said path;
- (d) actuating means for actuating the movement of said blocking member toward and away from said position thereof; and
- (e) yieldably resilient means urging said blocking member into engagement with said guide rails during said movement thereof.

2. An arrangement as set forth in claim 1, wherein said actuating means is electromagnetically operated.

3. An arrangement as set forth in claim 2, wherein said actuating means include a coil of conductive material having an axis extending in the direction of said path and axially spaced from said blocking member, and an armature linked to said blocking member.

4. An arrangement as set forth in claim 3, further comprising linkage means interposed between said armature and said blocking member for moving said blocking member toward said blocking position thereof when said coil is energized, and return spring means urging said blocking member to move away from said position.

5. An arrangement as set forth in claim 1, wherein said path defining means include a support member formed with a bore having an orifice in a face of said support member, said bore constituting a portion of said path, and said guide rails being mounted on said face for guiding said blocking member toward and away from a position in which said blocking member obstructs said orifice.

6. A releasable stop arrangement for a machine tool comprising, in combination:

- (a) stationary frame means;
- (b) a carrier arranged for reciprocating movement on said frame means;
- (c) a plurality of abutment members projecting from said carrier in the direction of movement thereof, said abutment members being juxtaposed transversely of said direction for movement in respective parallel paths when said carrier reciprocates on said frame means;
- (d) a pair of spaced guide rails extending transversely of each of said paths;
- (e) a plurality of blocking members movable on respective pairs of said guide rails toward and away from respective positions in which said blocking members block the paths of respective associated abutment members;

(f) a plurality of actuating means operable for actuating movement of respective blocking members toward and away from said positions thereof; and

(g) yieldably resilient means urging each blocking member in the direction of said reciprocating movement into engagement with the associated pair of guide rails during said movement of said blocking member.

7. An arrangement as set forth in claim 6, wherein two of said abutment members extend different distances from said carrier in a direction toward the associated blocking members.

8. An arrangement as set forth in claim 6, further comprising control means operatively connected to said plurality of actuating means for operating said actuating means in timed sequence.

9. A releasable stop arrangement for a machine tool and the like comprising, in combination:

- (a) means defining a path of movement for an abutment member;
- (b) guide rail means elongated in a direction transverse of said path;
- (c) a blocking member movable on said guide rail means toward and away from a position in which said blocking member blocks said path;
- (d) electromagnetically operating actuating means for actuating the movement of said blocking member toward and away from said position thereof, said actuating means including
  - (1) a coil of conductive material having an axis extending in the direction of said path and axially spaced from said blocking member,
  - (2) an armature, and
  - (3) linkage means interposed between said armature and said blocking member for moving said blocking member toward said position thereof when said coil is energized, and
  - (4) return spring means urging said blocking member to move away from said position thereof,
  - (5) linkage means including a lever arranged for pivoting movement relative to said guide rail means, and having two arms respectively connected to said armature and to said blocking member; and
- (e) yieldably resilient means urging said blocking member into engagement with said guide rail means during said movement thereof.

10. A releasable stop arrangement for a machine tool and the like comprising, in combination:

- (a) means defining a path of movement for an abutment member;
- (b) guide rail means elongated in a direction transverse of said path;
- (c) a blocking member movable on said guide rail means toward and away from a position in which said blocking member blocks said path;
- (d) electromagnetically operated actuating means for actuating the movement of said blocking member toward and away from said position thereof, said actuating means including
  - (1) a coil of conductive material having an axis extending in the direction of said path and axially spaced from said blocking member,
  - (2) an armature, and
  - (3) linkage means interposed between said armature and said blocking member for moving said blocking member toward said position thereof when said coil is energized, and
  - (4) return spring means urging said blocking member to move away from said position thereof,
  - (5) said linkage means including a bellcrank lever arranged for pivoting movement relative to said guide rail means about a fixed axis and having

two arms, one of said arms being connected to said armature, and a link member attached to said blocking member and hingedly secured to the other arm of said bellcrank lever;

(e) yieldably resilient means urging said blocking member into engagement with said guide rail means during said movement thereof, and engaging said link member for urging rotation thereof relative to said other arm.

11. A releasable stop arrangement for a machine tool and the like, comprising, in combination:

(a) means defining a path of movement for an abutment member, said path defining means including

(1) a support member formed with a bore having an orifice in a face of said support member, said bore constituting a portion of said path, and with an opening;

(b) guide rail means elongated in a direction transverse of said path, said guide rail means being mounted on said face;

(c) a blocking member movable on said guide rail means and guided thereby toward and away from a position in which said blocking member obstructs said orifice;

(d) actuating means for actuating the movement of said blocking member toward and away from said position thereof, said actuating means including

(1) a housing secured to said support member,

(2) a coil of conductive material arranged in said housing,

(3) an armature arranged for movement when said coil is energized, said armature extending into said opening, and

(4) a bellcrank lever pivoted on said support member in said housing, said lever having two

5

arms respectively connected to said armature and to said blocking member; and

(e) yieldably resilient means urging said blocking member into engagement with said guide rail means during said movement thereof.

12. An arrangement as set forth in claim 11, wherein said housing is formed with a bore aligned with said bore of said support member and constituting another portion of said path.

13. A releasable arrangement for a machine tool and the like comprising, in combination:

(a) means defining a path of movement for an abutment member;

(b) a guide rail elongated in a direction transverse of said path;

(c) a blocking member movable on said guide rail toward and away from a position in which said blocking member blocks said path;

(d) actuating means for actuating the movement of said blocking member toward and away from said position thereof; and

(e) yieldably resilient means urging said blocking member in the direction of said path into engagement with said guide rail during said movement of said blocking member.

arms respectively connected to said armature and to said blocking member; and

(e) yieldably resilient means urging said blocking member into engagement with said guide rail means during said movement thereof.

12. An arrangement as set forth in claim 11, wherein said housing is formed with a bore aligned with said bore of said support member and constituting another portion of said path.

13. A releasable arrangement for a machine tool and the like comprising, in combination:

(a) means defining a path of movement for an abutment member;

(b) a guide rail elongated in a direction transverse of said path;

(c) a blocking member movable on said guide rail toward and away from a position in which said blocking member blocks said path;

(d) actuating means for actuating the movement of said blocking member toward and away from said position thereof; and

(e) yieldably resilient means urging said blocking member in the direction of said path into engagement with said guide rail during said movement of said blocking member.
